(57) **CLAIM**

The ornamental design for a support element for supporting stabilator pistons of an axial bearing in a rock drill, as shown and described.

DESCRIPTION

FIG. 1 is a perspective top view of a support element for supporting stabilator pistons of an axial bearing in a rock drill showing our new design;

FIG. 2 is a perspective bottom view thereof;

FIG. 3 is a top side view thereof;

FIG. 4 is a rear side view thereof;

FIG. 5 is a front view thereof;

FIG. 6 is a bottom view thereof;

FIG. 7 is a bottom side view thereof; and,

FIG. 8 is a top rear view thereof.
